Primary Examiner—Wallace R. Burke*Assistant Examiner*—Lavone D. Tabor*Attorney, Agent, or Firm*—Marshall, O'Toole, Gerstein,
Murray & Borun[57] **CLAIM**

The ornamental design for a sponge mop squeeze plate with handle grip, as shown and described.

DESCRIPTION

FIG. 1 is a top, front and left side perspective view of a sponge mop squeeze plate with handle grip showing my new design;

FIG. 2 is a top plan view thereof;

FIG. 3 is a left side elevational view thereof with the right side being a mirror image thereof;

FIG. 4 is a bottom plan view thereof;

FIG. 5 is a front elevational view thereof; and,

FIG. 6 is a rear elevational view thereof.

The portions of a sponge mop and mop handle shown in broken lines in the drawings is for illustrative purposes only and forms no part of the claimed design.
